FIG. 1 is an elevational view of one side of a heel insert for a shoe sole showing my new design;
FIG. 2 is an elevational view of the other side thereof;
FIG. 3 is a top plan view thereof;
FIG. 4 is a rear elevational view thereof;
FIG. 5 is a cross sectional view taken along line 5—5 of FIG. 1;
FIG. 6 is a cross sectional view taken along line 6—6 of FIG. 1;
FIG. 7 is an elevational view of one side of a second embodiment of a heel insert for a shoe sole showing my new design;
FIG. 8 is an elevational view of the other side of the second embodiment;
FIG. 9 is a top plan view of the second embodiment;
FIG. 10 is a rear elevational view of the second embodiment;
FIG. 11 is a cross sectional view taken along line 11—11 of FIG. 7; and,
FIG. 12 is a cross sectional view taken along line 12—12 of FIG. 7.
The broken lines showing the remaining portions of the sole and shoe upper in FIGS. 1—12 form no part of the claimed design.
